ONE-THIRD TO NEILS PETER SORENSEN, OF PORTLAND, OREGON.

DOORS FOR UNDERGROUND ELEVATORS AND SHAFTS.

1,178,814.

Specification of Letters Patent. Patented Apr. 11, 1916.

Application filed July 8, 1915. Serial No. 38,797.

To all whom it may concern:

Be it known that we, WILLIAM F. MAU and HANS C. ANDERSON, citizens of the United States, and residents of Portland, county of Multnomah, and State of Oregon, have invented a new and useful Improvement in Doors for Underground Elevators and Shafts, of which the following is a specification.

10 Our invention relates generally to underground shafts or elevators, and concerns the safety of the persons working in the elevator pit.

One of the main objects of our invention 15 is the providing of auxiliary safety doors which will prevent the accidental stepping of a person into an open shaft, or the accidental dropping of goods down the shaft while the outer doors are open, and at the same time 20 affording ample ventilation and preventing rodents from entering the shaft. Our door feature may, of course, also be used independently of any elevator. We obtain this and other objects of our invention by combining with the shaft, outer and inner doors, 25 covering the latter with screen, and using for our purpose the combination of parts hereinafter fully described.

In the accompanying drawings, constituting 30 a part of this specification, Figure 1 is a vertical section on the line 1—1 of Fig. 2, showing an elevator pit or shaft extending from the sidewalk to the basement; the top of the shaft being provided with inner and 35 outer doors of our invention, such doors being shown in their lifted position in dotted outline, and the elevator being shown in both its up and down position, the former being indicated in dotted outline. Fig. 2 is 40 a top view of the elevator shaft looking down on the sidewalk with the outer doors removed, and the inner screen doors being shown as closed. Fig. 3 is a vertical section taken on the line 3—3 of Fig. 2, and, Fig. 4 45 is a similar section taken on the line 4—4 of Fig. 2.

50 *a* represents the sidewalk, *b* the floor of the basement, *c* the vertical guide-ways or posts, *d* the elevator floor, *e* the uprights of the frame mounted on the elevator the top of such frame members *e* being united by a curved or bow-piece as shown at *f*.

g g represent a pair of screened inner doors which are connected by hinges *g²* to the metal frame *h*, set in the sidewalk at 55 the top of the elevator shaft. The inner doors *g g* are provided with slots *i*, and on the bottom of these doors there is fastened a flat strip of spring metal *j* (see Fig. 4) which yieldingly bears against the guide-ways *c* permitting the doors *g g* to be opened and closed over the top of such guide-ways, but at the same time constantly keeping the slots *i* closed so as to prevent rodents from 60 entering through slots when the outer doors 65 *k k* of the elevator are opened, and the inner doors closed. Angle members *g³* fixed on the inner door *g*, are adapted to engage the sides of the metal frame *h*, when said doors are closed so as to hold the doors from fall- 70 ing into the shaft.

The outer doors *k k* are connected by invisible hinge-arms *l* to said frame *h*, and such hinge-arms project through the slots *m* therefor provided in the inner grated 75 doors. On the under side of the latter are provided yielding straps *n* which normally close the slots *m*, so as to keep out rodents, but permit the opening and closing of the outer doors *k k* as illustrated in Fig. 3. 80 The outer doors are so hinged that when open they will recline outward off center, and thus remain open until manually closed. The hinge-arms *l* are located in recesses *o*.

In the operation of the elevator, it is 85 best that the outer doors be manually opened only, so as to make sure that no pedestrian is on the doors while the elevator is about to be lifted. When the outer doors are opened by means of the frame *e*, provided on the elevator, accidents are liable to happen. When the outer doors are open, they are connected by a cross-bar *k'*. The inner doors *g g* are so hinged as to be opened and closed by the raising and lowering of the 90 elevator and to rest against the standards of the frame *e*, provided on the elevator, while the latter is being raised and lowered, and while remaining in its up position; all 95 of these features being fully shown in Fig. 1. Wearing strips *g'* are provided on the lower side of the inner doors *g g* against which the curved frame member *f* bears 100 when the elevator is raised. Where our

door feature is to be used independently of an elevator, the slots *i* and the related resilient pieces *j* are of course, omitted.

We claim:

- 5 1. The combination with a shaft, of an inner pair of screen doors provided with slots, an outer pair of doors hinge-arms for the latter, such hinge arms projecting through said slots provided therefor in said screen doors, and resilient members on the latter covering such slots, yieldingly bearing against said hinge-arms.
- 10 2. The combination in an underground elevator of the character described, of an upright frame on the elevator, such frame provided with a curved top, an inner pair of doors provided with slots and hinged so as to be lifted and lowered by the raising and lowering of the elevator, an outer pair of doors, hinge-arms for the latter, such hinge-arms projecting through said slots
- 15 20

provided therefor in said inner doors, and resilient members on the latter covering said slots, and yieldingly bearing against said hinge-arms.

- 25 3. The combination in an underground elevator of the character described, including vertical guideways, an outer pair of doors, and hinge arms for the latter, of an upright frame on the elevator, such frame provided with a curved top, an inner pair of doors hinged so as to be lifted and lowered by the raising and lowering of the elevator, such doors provided with slots for the vertical guide-ways, slots for the hinge arms of the outer doors, and resilient members on the inner doors covering said slots and bearing yieldingly against said guide-ways and hinge-arms respectively.
